CLAIM

The ornamental design for a combined copying and sorting apparatus, substantially as shown.

DESCRIPTION

FIG. 1 is a top plan view of a combined copying and sorting apparatus showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a bottom plan view thereof.

FIG. 1.

FIG. 2.

FIG. 3.

FIG. 4.

FIG. 5.

FIG. 6.
